UNITED STATES PATENT OFFICE.

NATHAN E. GOLDFADDEN, OF CHICAGO, ILLINOIS.

FLASH-LIGHT DEVICE.

1,243,156.

Specification of Letters Patent. Patented Oct. 16, 1917.

Application filed May 20, 1916. Serial No. 98,966.

To all whom it may concern:

Be it known that I, NATHAN E. GOLDFADDEN, a citizen of the United States, and a resident of the city of Chicago, county of Cook, and State of Illinois, have invented certain new and useful Improvements in Flash-Light Devices, of which the following is a specification.

My invention relates to improvements in photographic flash-light devices, and has for its object the production of a device of this character which will be of simple construction, one which may be readily taken apart and confined in a small space for transportation or carriage in the pocket if desired, and one which will be efficient in use.

Other objects will appear hereinafter.

With these objects in view, the invention consists in the combinations and arrangements of parts hereinafter described and claimed.

The invention will be best understood by reference to the accompanying drawings forming a part of this specification, and in which,

Figure 1 is a vertical section through a flashlight device embodying the invention, and

Fig. 2 is an end elevation of the device.

The preferred form of construction, as illustrated in the drawings, comprises a comparatively thin, wide flat plate 1 of insulating material, fiber being preferably used. Provided centrally at the under side 35 of member 1 is a hollow cylindrical handle 2 open at its lower end. The handle 2 is formed of insulating material. Arranged at the upper end of said handle are two spaced parallel comparatively thin, wide terminals 40 3 and 4, which are secured to said handle by means of rivets 3' and 4' respectively. The terminals 3 and 4 project through slits 5 and 6 which are formed in the member 1, snugly engaging therewith so as to serve to 45 lock the parts together, through friction. The arrangement is such, however, that when desired, the member 1 may be moved upwardly from engagement with the terminals 3 and 4, in which case the device will 50 occupy a very small space so as to permit of ready carriage in the pocket or other place for transportation.

Mounted in the handle 2 is an ordinary

dry battery or cell 7, held therein by the screw cap 8 which closes the lower end of 55 said handle, said cap being threaded upon a ferrule 9 which is secured to said end of said handle.

The terminal 3 is formed with a depending tongue 10 which projects through the 60 upper end of the handle 2 for engagement with the upper pole 11 of the battery 7. A helical compression spring 12, arranged in the lower end of the handle, engages with the lower end of said battery to press the 65 pole 11 in contact with the projection 10 of terminal 3. The opposite pole of the battery 7 is engaged by the spring 12 which serves as an electrical conductor for conducting the current from said pole to the cap 8. The latter, in turn, is adapted to conduct the current to the ferrule 9, said ferrule being connected with the lower end of a strip 13 of conducting material provided at 75 the inner side of handle 2 which extends upwardly and connects with one side of a manually operable switch 14 of approved design which is mounted upon the outer side of the handle. The opposite side of said switch is 80 connected by a conductor bar 15 with the terminal 4. By this arrangement then, it will be seen, that a circuit is completed between the terminals 3 and 4, through the battery, which circuit may be opened or 85 closed by simply shifting the movable control member 14' of the switch 14.

Coöperating with the upper ends of terminals 3 and 4 is a fuse wire 16. Said fuse wire is wrapped upon a spool 17 which is 90 loosely mounted in a bracket 18 secured to the under side of member 1. The fuse wire is passed from said spool upwardly through an opening 19 in the member 1, being thence engaged with tapering slots 20 which are 95 formed for the reception thereof in the upper ends of terminals 3 and 4. When thus engaged with the terminals 3 and 4, it will be seen, that said fuse wire will serve to electrically connect said terminals, and so 100 that, upon closing of the switch 14, the current flowing through said fuse wire will heat the latter to incandescence. In use, the flash powder is placed centrally upon the support 1 around the terminals 3 and 4, so 105 that, upon the heating of the fuse wire to

incandescence, as just described, the flash powder will be exploded. In order to prevent the fuse wire becoming buried too deeply in the flash powder, which is placed upon the support, and thus smother the same, the terminals 3 and 4 are formed with openings 21 below the slots 20, through which a portion of the powder deposited upon the support, will flow outwardly, leaving only a sort of hill between said terminals, the central portion or peak of which will engage with the fuse wire.

When the flash takes place, the fuse wire between the terminals is generally melted or fused. When this occurs, it is only necessary to unwind a fresh portion of said fuse wire and engage the same with the terminal slots 20. The bracket 18, which supports the spool 17, is formed with a depending flange 22 which serves as a shield to prevent injury to the fuse wire upon said spool by any flash passing through the opening 19, when the explosion takes place.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I

claim as new and desire to secure by Letters Patent is:

1. A flash-light device comprising a support for flash powder; a handle for said support depending therefrom; an electric battery mounted in said handle; a pair of 40 comparatively thin, wide spaced parallel terminals interposed in the circuit of said battery and projecting upwardly from the upper end of said handle through said support; a fuse wire adapted to connect said terminals; tapering slots in the upper ends of said terminals for the reception of said fuse wire, there being openings in said terminals below said slots; and a switch for controlling said circuit, substantially as described. 45

2. A flash-light device comprising a support for flash powder; an electric battery; a pair of spaced terminals interposed in the circuit of said battery and arising from said support; and a fuse wire adapted to connect said terminals, there being openings in said terminals below said points of engagement therewith of said fuse wire, substantially as described. 55

In testimony whereof I have signed my name to this specification in the presence of two subscribing witnesses.

NATHAN E. GOLDFADDEN.
